UNITED STATES PATENT OFFICE.

EDWIN G. PICKERING, OF MONTGOMERY COUNTY, NEAR DAYTON, OHIO.

IDENTIFYING-CARD.

1,228,817.

Specification of Letters Patent. Patented June 5, 1917.

Original application filed December 21, 1916, Serial No. 138,255. Divided and this application filed March 24, 1917. Serial No. 157,110.

To all whom it may concern:

Be it known that I, EDWIN G. PICKERING, a citizen of the United States, residing in the county of Montgomery, near the city of Dayton, Ohio, have invented a new and useful Improvement in Identifying-Cards, of which the following is a specification.

This invention relates to a new and useful improvement in identifying cards.

10 The principal object of my invention is to provide a simple and efficient identifying card which may be readily and firmly attached to the coat of the wearer for the purpose of identifying him to his fellows on all occasions. As distinguished from my other inventions in this art, the present one comprises an identifying card that contains a round aperture for coöperation with a bent element attached within the buttonhole of a 20 coat lapel, said element to be turned from view when not in use.

The preferred form of embodiment of my invention is illustrated in the accompanying drawings, of which Figure 1 is a vertical plan view of my identifying card containing a round aperture in the upper central portion thereof. Fig. 2 is a side view of the form of pin preferred to fasten the card to the lapel of a coat. Fig. 3 is a plan view of 30 a coat to the lapel of which my identifying card is attached. And Fig. 4 is a vertical section taken through said lapel, showing how the card is attached thereto, as well as the position of the head of said pin when 35 not in use.

Throughout the specification and drawings similar reference characters denote corresponding parts.

In a detailed description of the preferred 40 form of embodiment of my invention, the numeral 1 designates a card preferably rectangular in shape to receive vertically, the name of the person to be identified by it. (See Fig. 1.)

45 In the upper central portion of the card 1 a round hole 2 has been preferably provided to easily receive the head of a bent pin 3. Referring to Fig. 2, this pin is preferably an ordinary one whose shank is bent 50 at its upper end to form a bent or cranked portion which is adapted to project beyond

the buttonhole of a coat lapel 4 when its lower end is embedded in the fabric as shown in Fig. 4.

When the pin 3 is not in use the head 55 thereof is preferably behind the coat lapel 4 as shown in dotted lines in Fig. 4, thereby being concealed from view. Now, when it is desired to attach the identifying card 1 to the coat lapel 4, the wearer merely gives 60 the bent portion of the pin a half turn, which brings its head through and beyond the buttonhole, into a position to receive the round hole 2 of the card. The head of the pin is then passed through said hole to 65 permit its bent portion to firmly support the card which will, like a pendulum, normally hang therefrom in a vertical position. Gravity therefore maintains the card in a vertical position, a flattened pin such as was 70 employed to hold the card firmly in a horizontal position in my application Serial No. 138,255, from which the present one is divided, not being necessary.

I do not wish to be limited to the details of construction and operation herein shown and described, and any changes or modifications may be made therein within the scope of the subjoined claims.

Having described my invention, I claim: 80

1. An identifying card adapted to receive a name written in a vertical manner, and a cranked element coöperating with a hole formed in the top portion of said card, for firmly securing it in a vertical position to 85 the coat of the wearer.

2. An identifying card adapted to receive a name written in a vertical manner, and a cranked pin attached within a buttonhole of the wearer's coat, the head of said pin being 90 normally behind the latter and adapted to be turned through said buttonhole for passage through a hole provided in one end of the card, to firmly hold it in a vertical position on said card. 95

In testimony whereof I have hereunto set my hand this 22 day of March, 1917.

EDWIN G. PICKERING.
